HEAT-SEALING MACHINE

Walter Haas, Middletown, and Frank D. Bergstein, Hamilton, Ohio, assignors to The Interstate Folding Box Company, Middletown, Ohio, a corporation of Ohio

Application March 15, 1950, Serial No. 149,708

10 Claims. (Cl. 154—42)

1 Our invention has to do with the joining of juxtaposed portions of amorphous films by heat so as to provide seams therein. While the invention set forth herein is of utility in the formation of any structures requiring continuous, longitudinal seams, we shall describe it in an exemplary embodiment having to do with the manufacture of lining tubes or bag-like liners for paperboard cartons such as are in wide use for frozen foods or other products which must be protected from gain or loss of moisture and from deleterious external influences.

Hitherto there has been a wide use of various amorphous or non-fibrous films of commerce in the manufacture of liquid-tight or moisture-tight bags for such uses. Certain types of films offer little difficulty in the formation of heat-sealed longitudinal seams. For example, cellophane coated with a fusible sealing substance, is readily tubed and is readily sealed by the application of pressure and sufficient heat to melt or soften the sealing substance, the film itself retaining its strength substantially unimpaired throughout the sealing operation. Other films have the property of softening sufficiently to become sealed together while retaining over a wide range of temperature sufficient inherent strength to be handled without disruption at the seam area.

There are, however, certain types of film, desirable for various qualities of proofness, strength, inertness, non-toxicity and the like, which have only a very narrow range of temperature lying between a solid condition and a very soft condition in which they are non-self-sustaining. Such films, when heated, lose their strength very rapidly, so that handling becomes difficult. They also become sticky when heated, so that it is difficult to separate the joined parts from the seam-forming instrumentalities in the heat softened condition of the seamed parts. Also, on slight overheating, such films tend to liquefy and even to collect in droplets or to pull apart through surface tension effects, thus destroying the integrity of the films and the seams formed therein. These difficulties have presented serious problems to the practical art, and in the case of some films have hitherto prevented the formation of adequate seals or seams by machinery in automatic or continuous operation.

An example of such a film, presenting the above difficulties in a high degree, is a film of polyethylene. Polyethylene in thin films is quite strong at room temperatures and is highly desirable by reason of its proofness and other char-

acteristics for the manufacture of liquid-tight and moisture-tight bags. But it is inherently readily fusible, in the sense that the application of heat sufficient to soften the material for sealing purposes is likely, unless controlled more exactly than has hitherto been possible in automatic machines, to soften it too much, rendering the production of seams impossible, or producing seams which are not sound. Pliofilm, which is an amorphous film formed from chlorinated rubber hydrocarbon, presents similar difficulties, although in somewhat lesser degree, and is of that type of film which for convenience hereinafter we shall refer to as "readily fusible."

2 The primary object of our invention is to provide a seaming method and mechanism for readily fusible films whereby adequate and reliable continuous seams may be formed therein with the avoidance of the difficulties we have discussed. With coated films, such as the so-called moistureproof cellophane, no substantial difficulty is encountered in tubing the material and forming a longitudinal center seam. The chief problem arises in the making of end closures on bag lengths cut from the bag tube, where the inclusion of folds or lapped portions in the closure may give rise to difficulty, especially where the thickness of the fusible coating is less than the thickness of the cellophane itself. Conversely, in the end closing of bag tubes made of readily fusible films, the fusibility of the body of the seam diminishes the difficulty with folds and lapped portions. But great difficulty is encountered in the formation of continuous longitudinal seams in bag tubes, so much so that we are not aware of any previously successful endeavors to make longitudinal seams automatically and by the use of apparatus. It has been suggested to join paper strips to the edges of a strip of polyethylene, for example, so that the heat could be applied through the paper strips, and so that these could assist in the transportation of the material over a former. This, however, is both expensive and inconvenient, and at the same time interferes with the formation of end closure seams on the bag tubes.

The primary object and other objects of the invention, which will be made clear as the description proceeds, or will be apparent to one skilled in the art upon reading these specifications, we accomplish in that procedure and by the use of that mechanism of which we shall now describe an exemplary embodiment. This embodiment will have to do with the manufacture of continuous lengths of bag tubes, which

may be cut apart into bag lengths as desired. Reference is made to the accompanying drawings wherein:

In the sealing of polyethylene films by heat, there is a spread of only about 5 degrees between a condition of the material too solid to weld together and a condition of the material too soft to maintain its integrity when handled on conventional sealing apparatus. This has hitherto rendered the continuous or automatic sealing of polyethylene films impracticable.

Briefly, in the practice of our invention, we have found that successful and entirely dependable heat-welded seams may be formed in such films as polyethylene which are very readily fusible if mechanism is employed such as hereinabove described. In one aspect of this mechanism and procedure, the film is pulled over a former, and the lapped portions are supported from beneath by moving means. A heat conducting element is caused to travel with lapped portions of the film over the area of seam formation, heat is applied through the heat conducting element by a heating means of narrower effective width and arranged to apply the heat intermediate the edges of the traveling member so that a heat gradient is established in the traveling member and in the lapped portions of the film, and the welded seam is allowed to travel with the moving members until the fused parts have congealed or hardened before separation therefrom. By means and a method such as have just been briefly characterized, we can continuously and perfectly form welded seams in polyethylene film materials without the use of protective paper strips or other extraneous elements. We shall now proceed to a more particular description of the mechanism and method by which this is accomplished.

Referring to Figures 1 and 2 we have shown a machine having a general frame 30. A polyethylene or other readily fusible film material 31 is withdrawn from a supply roll journaled between supports on the machine frame, is carried over a reversing roll 32 and downwardly beneath a forming plate 33, having an upturned front end, about which plate the film is to be tubed.

The forming plate is shown as supported by a post 34 at one end, engaged by a bracket 35 on a shaft or rod 36, which in turn is held by a bracket 37 on a shaft 38 extending across between the machine supports 39 and 40, and by other shafts and supports as may be required. The forming plate and the material extending beneath may be supported from below by a series of rolls 41, 42, 43, journaled in any suitable way in connection with the machine frame, and driven if desired. The driving of these rolls, while not usually necessary, assists in the passage of the film through the machine.

The film material 31 is folded about the forming plate 33 as is usual in bag tubing operations, by folding fingers 44 and rollers 45 mounted in suitable brackets on the shaft or rod 36. Our forming plate 33 is unusual in that it is preferably formed, in an area underlying the area of seam formation, with a plurality of small transverse rollers, one of which is shown at 46 in Figure 8, acting at the top surface of the forming plate to form a moving support for the lapped material

thereon while it is being welded together. The rollers are small in diameter; and they and their mountings preferably do not significantly increase the effective thickness of the forming plate. There are many ways of mounting such rollers. One way is illustrated in Figures 6 and 10 where the forming plate 33 is cut away as at 47, and the several small rollers 46 are journaled at the apices of their tapered ends in bars 48 and 49. These bars have bifurcated ends, e. g. 48a which, as most clearly shown in Figures 10 and 11, engage and clamp edge portions of the forming plate 33 adjacent the cutout 47. Enlargement of the cutout as at 33a permits the insertion of the bars 48 and 49 and the assembly of the rollers 46 thereto. The clamping may be accomplished by screws 50 engaging the bifurcated ends of the bars.

As will be clear from Figure 6, the rollers 46 form a moving support for the lapped portions of the folded film 31 beneath the area of seam formation. The small individual rollers may be made of steel or other metal. In the mode of mounting these rollers illustrated in our drawings, they serve to conduct heat from the seam so that it may be absorbed and dissipated by the forming plate. Their primary purpose, however, is to hold the film layers up into contact with an overhead metal belt which will subsequently be described. They play an important part in the sealing for this reason, particularly inasmuch as they provide support practically free from frictional resistance. When irregularities in the formation or position of the overhead belt are likely to be encountered, we prefer to mount the rollers resiliently or to provide resilience in the surfaces of the rollers themselves. The latter may be accomplished, as shown in Figures 8 and 11, by reducing somewhat the midsection of the rollers, as at 46a, and placing over them a sleeve 46b of rubber or other resilient material.

Also, we prefer to form a groove (33b in Figures 10 and 11) in the former extending forwardly of the place at which the rollers 46 are mounted. This slot or groove, underlying the lapped edges of the film material in the area of seam formation, serves as a vent and also as a clearance for the film while the material in the seam is still softened.

Figure 6 also illustrates one mode of applying heat to lapped portions of the film to effect a weld or seam in accordance with our invention. Directly above and in contact with the lapped portions of the film 31, we have shown in section in this figure a traveling metallic belt 51 having good heat conductivity. Above the belt there is located an electric or other heater 52 having a nose or heat applying means 53 in contact with the belt 51 centrally thereof, and substantially narrower than the belt. The heater 52, if electric, will preferably be supplied with thermostatic control means (not illustrated), and as shown in Figure 5, the power supply circuit 54 being provided with a variable resistance 55 or other reactor for the purpose of accurate heat control. By way of example, in our practice we are successfully employing as the moving member 51 an endless steel belt .008 inch in thickness and $\frac{3}{4}$ of an inch wide. The contacting nose 53 of the heating element 52 is only $\frac{1}{8}$ inch in width. These dimensions are exemplary merely, and may be widely varied not only for the same material, but in connection with changes in the thickness of the film, the desired width of actual fusion

in the seam, the heat transmittivity of the substance of the belt 51 and the like.

It will be noted that the heat transmitting nose 53 does not contact the edges of the belt 51, but serves to heat only the central portion of the belt. Heat sufficient to fuse the substance of the lapped portions of the film is transmitted only through the central portion of the belt 51, and a temperature gradient is established by the belt due to the loss of heat at the edges thereof by radiation and conduction. The edges of the belt are therefore substantially cooler than the longitudinal central portion of the belt over the welding area and in particular the edges of the belt are maintained below the temperature required to soften the material of the film to welding or fusion consistency. This condition is one easily attained with the apparatus and in the method described herein. Where a heating element of fixed width and uniform temperature is applied to the films, difficulties are had, as already explained, with excess fusion of the film substance, and these difficulties are greatest along the side edges of the heating element. Our procedure and apparatus entirely obviate these difficulties and result in the application of heat to the lapped portions of the film in accordance with a gradient curve indicating a gradual lowering of temperature from a welding heat adjacent the center of the belt to temperatures outwardly therefrom at both sides which temperatures are well below the fusion temperature of the material.

Since it is driven at the same speed as the moving film, the element 51, traveling with the lapped portions of the film, does not tend to disrupt them by physical interference, but rather to maintain the softened portions of the film in position during the welding operation. As will hereinafter be explained, cooling may be applied to the welded seam through the belt element 51 beyond the welding zone so as to cause the welded parts to harden or congeal fully prior to their separation from the belt. Thus the development of stickiness in the film material adjacent the under surface of the belt in the welding zone is not of consequence, and does not lead to the disruption of the film. The small rollers 46 are highly important in the seam forming operation since they exert no frictional resistance on the softened film portions, have minimum contact therewith, and continuously present fresh, cool surfaces to the film.

The traveling member 51, the heating means and the cooling means are preferably mounted as a unit in such fashion that they can be brought into contact with the work and removed from contact therewith at will. In Figures 4 and 5 we have shown the belt element 51 passing over sheaves 56 and 57 which are mounted on stub shafts 58 and 59 on a bar or frame element 60, a preferred shape of which is most clearly shown in Figure 1. This bar or frame element, hereinafter simply called the bar 60, is freely pivoted at one end on a shaft 61 which extends across the machine and is journaled in brackets 62 and 63 (see Figure 1) on the machine frame. The mounting of the bar 60 on the shaft 61 provides for a downward swinging of the upper sealing apparatus into contact with the work on the forming plate 33, or an upward swinging of the apparatus out of contact with the work, the swinging from position to position being controlled as later described.

The belt 51 will be driven, and to this end we

have shown, most clearly in Figures 4, 5 and 7, a sprocket 64 attached to the sheave 57 and mounted on the stub shaft 61. This sprocket is connected by a chain 65 to a sprocket 66 fixed on the shaft 61. As shown in Figure 1, the shaft 61 may bear another sprocket 67 connected by a chain 68 to a sprocket 69 on a main drive shaft 70.

The heater 52 may be mounted directly upon a stud on the bar 60 if desired. However, we have found it preferable to provide a means whereby the pressure of the nose of the heating element can be regulated against the belt 51, and whereby the heater can be moved out of contact with the belt where this may be desired. To this end, as more particularly illustrated in Figure 6, we mount the heater 52 on a yoke 71 which in turn is mounted on a stud 72 on a lever arm 73. The lever arm is pivotally mounted on the stub shaft 59 which holds the sheave 57, either directly or adjustably by means of a guide 74, the lever arm 73 being slotted, as shown, to permit movement with respect to the guide.

The yoke 71 has upstanding ears 71a and 71b engaging the stud 72. The ear 71b is provided with a vertically elongated slot through which the stud 72 passes, and a compression spring 75 engages between the lever arm 73 and the ear. This construction permits an up-and-down movement of the right-hand end of the yoke 71, as illustrated in Figure 6, the result of which will be a tilting of the heater 52 and hence a lateral adjustment of the position of its nose 53 with respect to the moving belt 51. This adjustment may be accomplished by providing a laterally extending ear 71c on the yoke which is engaged from beneath by a set screw 76 threaded in a bracket 77 on the lever arm 73.

The opposite end of the lever arm 73 may be connected by means of a tension spring 78 (Figure 5) to an arm 79 on a bar or angle iron 80 extending across the machine. A bar 81, also attached to the angle iron 80, has pivoted to its lower ends a lever arm 82 having a downwardly depending, bifurcated end, within which is mounted a roller 83 bearing against the left-hand end of the lever arm 73. An upwardly turned portion of the lever 82 may be engaged for adjustment by a thumb nut 84 or the like on an eye bolt 85 engaging the bar 81. A spring 86 may be interposed between elements 82 and 81, as shown. By means of the thumb nut the position of the lever 82 may be adjusted so as to regulate the pressure of the heater 52 against the belt 51, and to lift it entirely from the belt, in the lower position of the mounting bar 60. When the mounting bar 60 is swung to its raised position, the roller 83, mounted as described on the stationary angle iron 80, will act to raise the lever arm 73, removing the heater 52 from contact with the belt 51.

The lever arm 73 is provided with a lower extension 73a underlying the shaft 61, by means of which the heater may be raised out of contact with the belt 51 by mechanism hereinafter described.

The sealing of readily fusible films is a very delicate operation, and it has been found that during stoppages of the machine, the bare removal of the nose 53 of the heater a short distance from the belt 51 may not be sufficient to prevent building up of heat in the belt. As a consequence, we prefer to provide a shield which,

when the heater 52 is raised as hereinafter described, will automatically swing into position between the heater and the belt and which will likewise be automatically removed from shielding position when the heater is lowered to operating position. To this end we provide a shield element 87 attached to a bar or lever 88 which is pivoted as at 89 to an extension or crossbrace of the mounting bar 60. A tension spring 90 (Figure 1) engages the bar 88 and tends to urge it to a position in which the shield is off-side.

Referring to Figure 1, we have shown a sliding element 91 mounted on the shaft 61. This sliding element is connected by a link to one arm of a three-arm bell-crank 93 pivoted in a bracket on the machine frame. Another arm of the bell crank is connected by a link 94 with the operating lever 95 of a clutch mechanism 96 interposed between the shaft 70 and a drive pulley 97 which may be belted to a prime mover (not shown).

The sliding element 91 is connected to the shield lever 88 by a link 98. Also the sliding element 91 is provided with a conical nose 99 capable of engaging the lower extension 73a of the heater-bearing arm 73.

The arrangement is such that when the clutch operating lever 95 is swung to the "off" position, (a) the clutch 96 is disengaged and the machine stops, (b) the element 91 is slid along the shaft 61 until the nose 99 contacts and depresses the extension 73a of the lever arm 73, thus raising the heater 52 away from the belt 51, and (c) the lever 88 is swung so as to interpose the shield 87 between the heater and the belt. A reversal of these operations occurs automatically when the clutch operating lever is moved to the "on" position.

In Figures 4 and 5, 100 represents a cooling shoe engaging the belt 51. It may be in the form of a hollow body having flexible conduits 101 and 102 for connection with a source of cooling fluid such as water, and with a drain. It may be mounted by bracket means 103 on studs 104 and 105 on the bar or frame 60, the bracket means being provided with springs and adjustment screws 106 as shown to regulate the pressure of the shoe 100 against the belt. The cooling capacity of the shoe, where employed, will be sufficient to lower all parts of the belt 51 passing beneath it to a temperature well below the welding temperature of the film.

For the adjustment of the tension of the belt 51 we may provide a screw-type adjustment means 107 in the bar or frame 60 engaging the stub shaft 58.

To assist in the removal of the formed seam from the belt 51, we may if desired provide an air blast device comprising a nozzle 108 (Figure 2) with a delivery end directed into the pinch between the belt and the seam at the exit side of the apparatus. This nozzle may be held in a bracket 109 on the bar 60 and provided with a flexible hose connection 110 to a source of air under pressure.

Apparatus such as that hereinabove described will dependably produce longitudinal seams in difficultly weldable material such as polyethylene or other films which are readily fusible. For machine threading purposes it is desirable to provide means for the removal of the whole upper sealing apparatus from proximity to the film, so that the disposition of the film on the former 33 can be adjusted. One way of accomplishing this is illustrated in Figures 1 and 2. Here an upstanding post 111, suitably mounted on the

machine carries adjustably a laterally extending arm 112, which is slotted to receive a handle 113 pivoted to the right-hand end of the mounting bar 69. The handle is notched at its upper end, a detent 114 is provided on the arm 112, a spring latch 115 is provided, cooperating with the detent, so that when the sealing mechanism is swung downwardly to operating position, it will be held there through the illustrated engagement of the handle element. A screw adjustment means 116 is provided on the post 90 for the positioning of the arm 112 thereon, so that the pressure of the sealing mechanism against the work can be accurately controlled. Usually the adjustment is made in such fashion that less than the full weight of the sealing mechanism is imposed on the work.

The sealing mechanism is counterbalanced in some suitable fashion. We have shown a cable 117 attached to the handle 113, passing over a pulley 118 on the arm 112 and another pulley 119 on a bracket on the machine frame, and bearing at its lower end a weight element 120 somewhat heavier than the effective weight of the sealing apparatus and its associated parts. Consequently, if the handle 113 be released, the sealing mechanism will be swung upwardly into inoperative position.

The tubed film is drawn through the machine by a pair of pinch rolls 121 and 122, one or both of which is driven. As the former bag tube is fed forwardly by the pinch rolls, it is cut into desired lengths for bags in any suitable way, as by a fly knife device 123, and delivered to a conveyor 124 having an upper pressure belt 125. The bag tube lengths may then be associated with cartons, if desired, in known ways, or otherwise employed as finished bag tubes.

Figure 9 is a cross-sectional illustration of a weld formed as at 126 in the film element 31 where its edges are lapped.

For most purposes the bag tubes will require a cross seam or seal at one end to convert them into operative bags. Such a bag is shown in Figure 3 at 127 where the longitudinal seam is indicated at 126 and the cross or end seam at 128. The continuous formation of end seams requires a change in the direction of motion of the bag tubes formed as hereinabove described. This is most conveniently accomplished by providing an angularly related machine section having a frame 129, as in Figure 1. The transfer of the bag tubes from one machine section to the other, however, involves a serious problem by reason of the flimsiness of the film material and the bag tubes formed therefrom. In providing angularly related sections on ordinary carton making machines, or on bag making machines where the material of the bag tubes is relatively stiff and self-sustaining, it is sufficient to feed the structures forwardly against a stop so that they overlie a second conveyor operating in the new direction. This, however, cannot be done simply with the extremely flexible bag tubes to which this invention is primarily addressed, especially where such tubes are made in large sizes. As a consequence, we have had to device special transfer mechanism which will now be described.

As will be evident from Figures 1 and 2, the conveyor elements 124 and 125, receiving the bag tubes from the fly knife mechanism 123, feed the tubes in an upwardly direction for transfer purposes. At the end of these conveyors, we prefer to provide a pinch roll feeder, indicated

most clearly in Figure 12 at 130 and 131. A second, or angularly related, conveyor is provided in the second machine section, and is shown as comprising a pair of chains 132 and 133 passing over suitably driven sprockets. An end stop or guide against which the bag tubes may be fed is indicated at 134. But unless some additional mechanism were provided to carry the bag tubes across the initial conveyor in the second section of the machine, they could not be brought to rest against the stop 134 so as to be engaged by the pins on the chains 132 and 133. Furthermore, the engagement of the pins with the extremely flexible bag tubes, so as to produce a sudden change in the direction of their motion, would tend to fold and distort them or cock them in various directions, so that a perfect end seal could not be made. In order to give to the bag tubes an initial tendency to follow the new direction of motion, the conveyor elements 132 and 133 are slanted downwardly in the new direction of motion, as will be best appreciated from Figure 13. To carry the tubes across the conveyor elements so that they may be positioned against the stop 134, we provide a gas blast mechanism, which tends to float the tubes across and also to assist in moving them against the stop 134. This mechanism comprises a series of air tubes 135 extending longitudinally of the conveyor formed by the elements 132 and 133 and having openings throughout their effective length, which openings are generally upwardly directed, as will be apparent from Figure 13. In connection with these tubes, we employ a series of vanes 136, one for each tube, which vanes are mounted on the tubes, extend generally in the same direction, and can be tilted on the tubes, being adjustably mounted thereon by releasable clamp means 137 (see Figure 14). The vanes, as will be apparent from Figure 12, are tilted upwardly in the direction of motion of the bag tubes as delivered by the first section of the machine, and they serve to direct the air blasts in the direction of motion of the tubes as so delivered. It will be readily understood from the above description that a flow of gas upwardly off the edge of each of the vanes tends to float the bag tubes across until they can be brought into contact with the stop device 134, while at the same time the tubes are not raised so high as to be out of contact with the pins on the conveyor elements 132 and 133.

The air tubes 135 may, as will be seen from Figures 13 and 15, be mounted upon cross elements or channels 138 and 139 on the machine by means of clips or brackets 140 which permit rotary adjustment of the tubes and hence the positioning of the orifices therein. We prefer, as shown in Figure 1, to connect the tubes 136 by individual conduits 141 and through individual valves 142 to a manifold 143, which in turn is connected through a pressure regulating valve 144 to a source of air or other gas under pressure, such as a pressure tank 145. A conditioning unit 146 may be interposed in this connection so as to control the temperature or the humidity of the air, or both, to the end of minimizing the effect of static in the bag tubes. The individual valves 142 permit the regulation of pressure independently for each of the tubes 136, as may be desired for accommodating the transfer mechanism to the handling of bag tubes of various sizes and various weights of material.

The downward sloping initial conveyor 132, 133 of the second section of the machine merges with

a horizontal conveyor comprising chains 147 and 148 shown in Figures 1 and 13. By the time the bag tubes, indicated in the latter figure at 149, reach the conveyor section 147, 148, they will be traveling in the required direction and at the proper orientation transverse the path of travel.

To sustain the bag tubes intermediate the chain elements 147 and 148, we may provide a table 150 or in lieu thereof a traveling belt element intermediate the chains. It is also within the scope of our invention to provide hold-down or moving clamping means in connection with the conveyor 147, 148 or with a traveling belt element forming a part thereof. By any of these means, the bag tubes, moving in succession in a direction transverse their length, may be carried through end sealing means, certain forms of which will now be described.

As in forming the longitudinal seam of a bag tube, it is quite possible in forming end closure seams to support the material on one side by means of a series of small spaced rollers while applying the seam forming heat to the opposite side through a metallic belt. But due to the extremely flimsy and flexible nature of the individual bag tubes, we prefer to engage them between concurrently traveling belts. To this end, as shown in Figure 16, we provide spaced sheaves 150 and 151 mounted in bearings adjustable in supports 152 and 153, and provide an upper belt element traversing these sheaves. The belt element is preferably metallic, as at 154, but in order to even the pressure, the metallic element may be faced with rubber or other resilient material 155. This construction is most clearly shown in Figure 17.

On the same standards or supports, we journal sheaves 156 and 157 for a belt 158 which is the belt through which the seam forming heat will be applied. The arrangement is such that an end of the bag tubes passing through this section of the machine (one of the tubes being indicated at 159) will be caught between the two belts. The sheaves 156 and 157 also have adjustable bearings preferably, and the entire standard or support 153 may be made longitudinally adjustable as at 160 on the bed 161 of the machine.

In order to hold the lower flight of the belt element 154, 155 down into contact with the end of the bag tube 159, we provide a series of small rollers 162. These rollers, as shown in Figures 16 and 19, are mounted in bifurcated elements 163 to which upwardly extending rods or shafts 164 are attached. These shafts pass through opposite sides of hollow bodies 165 and 166; they bear abutment means 167, and compression springs 168 (see Figure 18) surround the shafts or rods 164 engaging between the upper sides of the bodies 165 and 166 and the abutments 167 on the rods. Thus the rollers are urged downwardly under controlled pressure. In order to prevent cocking of the rollers, the bifurcated elements 163 may be provided with non-circular bosses 163a which engage in non-circular recesses in the bottom elements of the bodies 165 and 166. Other means of preventing cocking may be adopted, as will be evident.

The bodies 165 and 166 may be adjustably mounted as shown by means of threaded rods 70 and nuts on brackets 169 and 170 attached to a machine frame element 171.

The bag tubes pass through the machine section in Figure 16 in the direction of the arrow 172 and are engaged between the upper and lower

belts. The lower belt is provided with a heating element 173 similar to the heating element 52 described in connection with Figure 6, having a similar nose for contacting the belt and resiliently mounted on a bracket 174 by means of rods and compression springs, as will be clear from Figures 16 and 18. There is also provided in connection with the belt 158 a fluid cooling shoe 175. This may be resiliently mounted on the machine frame by bracket means 176 similar to the bracket means 163 hereinabove described.

The sheaves 150 and 158 are driven in synchronism so that the belts move together in that flight in which they simultaneously engage the end portion of the bag tube 159. This may be accomplished in various ways. We have shown the sheaves provided with sprockets 177 and 178, engaged and driven by a common chain 179 which will be understood as engaging a drive sprocket (not shown) affixed to one of the power shafts of the machine.

In the formation of end closure seams, it is as necessary as in the formation of longitudinal seams to provide a means whereby the heating element may be automatically withdrawn from the belt 158 when the machine is stopped for any reason. There are various ways in which this may be accomplished. We have illustrated one suitable mechanism in which the bracket element 174, which mounts the heating shoe 173, is in turn pivotally mounted to one end of a lever arm 180, as shown in Figure 18. The other end of the lever arm is pivoted to an element 181 slideable on a bracket 182 on the machine frame. Intermediate its ends, the lever arm 180 is pivoted to a link 183 which in turn is pivoted to the bracket 182. The arrangement is such that if the sliding element 181 is moved to the left in Figure 18, the link 183 will tend to swing the lever arm 180 downwardly, as shown in the dotted lines in that figure. Similarly, when the sliding element 181 is moved to the right in the figure, the link 183 will move the lever arm upwardly. An adjustable abutment is provided comprising a stop member 184, threaded into an ear 185 on the bracket 182 and provided with a locking nut. This abutment serves to limit the upward movement of the lever arm 180 to bring the heating shoe 173 to rest against the belt 158.

The sliding element 181 is arranged to be actuated in accordance with the clutch lever 95 controlling the main drive of the machine. In Figure 1 we have shown a third arm of the bell crank 93 connected by a link 186 with a bell crank 187, which in turn is connected by a link 188 to a bell crank 189. The last mentioned bell crank is connected by a link 190 to the sliding element 181. The elements 186 to 190, inclusive, as will readily be understood, simply form a transmission between the power control for the machine and the means for moving the heating shoe 173, and other transmissions may be substituted if desired.

In the making both of longitudinal welded seams and of transverse end closure seams, the application of heat for the purpose is a delicate operation. The heat has to be limited and controlled so as to prevent an unwanted fusion or softening of the film substance beyond the desired area of seam formation. At the same time, if the heat should be appreciably diminished by sporadic conditions, there will be insufficient to accomplish the welding, and the seam will be characterized by skips. The belts 51 and 158, through which the heat is transmitted to the film,

must be carefully and accurately made. Variations in thickness of the belts, such as may occur at welded bends in them, may be productive of skips; but it is readily possible by suitable grinding and dressing techniques to provide belts of constant and uniform thickness. In our initial work, when skips were encountered in the seam, it was at first believed that they might be due to failure of the supporting means to hold the film elements in accurate contact with the surfaces of the belts. It was later found, however, that the small rubber covered rollers 46 of Figure 8 and elements such as the rubber covered belt 154, 155 suitably backed by spaced rollers 162 acted sufficiently to maintain contact between the belts and the film portions. Where skips were encountered with carefully made belts of constant thickness, it was found that the difficulty lay rather in a lack of flatness in the belts themselves. Belts may become kinked or may acquire a permanent non-planar set in use. Such kinks or bends, passing through the welding zone, tend to displace the heating shoes and, therefore, interfere with the uniform application of heat to the film portions.

We have developed a mode and mechanism of applying heat to the sealing belts independently of belt displacement, as will now be described. Pursuant to this development, we do not employ a metallic heating shoe with a nose pressed against the belt, but instead, heat the belts by a flame so that the belts become uniformly heated irrespective of minor deviations of the belts from their true paths of travel.

Apparatus of this kind is illustrated in Figures 20 to 27 inclusive. We provide a trough-like element 191 which, as shown in Figure 23, is V-shaped in transverse vertical section. As shown in this figure and in Figure 24, the lower end of the trough is open in such manner as to form a slot 192 which is narrower than the belt 193. The belt 193 is the metallic belt through which heat will be applied to the film portions, and it may be either the belt 51 of Figure 6 or the belt 158 of Figure 16. One portion of the slot, i. e. that portion where the flame from a torch presently to be described impinges on the belt 193, may be made somewhat wider, as at 192a in Figure 24. The hollow walls of the V-shaped trough are filled with a cooling fluid 194 which is circulated. Trough element 191 rides upon the belt 192 in a manner similar to the noses of the heat shoes hereinabove described. But it will be seen that the lower edge portions of the trough, riding against the outer marginal portions of the belt, serve to cool these portions by conduction, while heat is applied to the belt centrally through the slot 192. In Figure 23 we have shown a bracket means 195 for mounting the trough, and a trough element 196 for applying the flame. The trough element may be mounted on the trough 191 or bracket 195 if desired, and the entire structure substituted for the heating shoes 52 and 173 of the various figures hereinabove described, flexible tubing provided for the torch gases and the cooling fluid 194, and these heating elements may be actuated in the same way and by the same mechanisms already set forth.

However, we prefer to mount the torch in a movable fashion on an external support so that upon stoppage of the machine, the torch tip may be swung out of the trough element 191 to some position in which it cannot apply heat to the belt. When this is done, the continuous

passage of cooling fluid through the trough element 191 will make it unnecessary to remove this element from the belt.

As shown in Figure 22, the mounting bracket 195 may be supported gimbalwise in the forked end of a lever arm 197 pivoted centrally on a support 198 attached to the machine frame. The other end of the lever arm may be connected by a tension spring 199 to an adjustment means 200 on a support, and an adjustable stop means may be provided to fix the lower portion of the trough element 191, as shown in this figure at 201. The trough element 196, having a curved end to enter the trough in the relationship shown in Figure 23, may be mounted upon an element 202 which is adapted to rotate. This element, as most clearly shown in Figure 20, is U-shaped or E-shaped and is affixed to a shaft 203 rotatively mounted in a bearing 204 on the machine. It will be evident that as the shaft 203 is caused to rotate, the torch may be swung from that position indicated in Figure 21 (corresponding to the operative position described in connection with Figures 23 and 24) to the position shown in Figure 25. For rotating the shaft, we affix to it a toothed pinion 205 which meshes with the teeth of a segment element 206 mounted so as to rock upon the shaft of a sprocket 207 carrying the belt 193, there being a spaced sprocket 208 for the return of this belt.

In the particular embodiment of Figures 20 to 26 inclusive, the belt 193 is illustrated as the upper belt of an end sealing device, there being a lower belt 209 provided with supporting rollers and shown in Figure 26. The upper belt element 193 may also be provided with a cooling shoe 210 mounted as hereinabove described. It will be understood that the upper belt and its appurtenances may be employed in lieu of the belt 52 and its appurtenances for the formation of longitudinal seams in the apparatus of Figures 1 and 2.

The sheave 201 is provided with a sprocket 211 connected by a driving chain 212 to a sprocket 213 on a shaft 214. For operating the torch, especially where the apparatus of Figures 20 and 21 is employed for the formation of longitudinal seams, we may provide an extension 215 adjustable with respect to the segment 206 and bearing a cam following roller 216 at its end. An element 217, slidable upon the shaft 214 and having a tapered nose 217a, is analogous to the elements 91, 99 hereinabove described in connection with Figure 1; and the sliding element 217 may be connected by a link to the bell crank 93 so that operation of the clutch lever 95 will result in swinging the torch 196 into and out of operating position. It will be understood that as the tapered nose of the sliding element 217 is moved against the cam follower 216, the segment 206 will be moved, operating the torch as aforesaid through the pinion 205 and the torch mounting element 202.

It is intended that the torch will remain burning throughout the entire operating period of the machine including such temporary stoppages as may be required for adjustment. As a consequence, when the torch is swung to the inoperative position, we prefer to provide a shield against which its flame may impinge. For simplicity, such a shield has not been illustrated in Figures 20 to 27; but Figure 28 shows the torch 196 in upraised position with its flame impinging against a shield element 218, faced as at 219.

with asbestos or other heating resistant refractory.

Flexible connections for the supply and withdrawal of coolant fluid to the cooling shoe 216 and to the trough-shaped element 181 have been shown in various of the figures, but do not require special description.

For operating the torch when our sealing mechanism is employed for the formation of end closure seams, a modified form of operating apparatus may be found desirable, and is illustrated in Figure 27. Here the torch 196 is mounted on the torch holding element 202 as before, and this, in turn, is mounted on the shaft 203. The pinion 205 on this shaft meshes 15 with a pinion 220 on a shaft 221 suitably journaled in bearing elements, not shown. The shaft 221 in this instance bears a cam element 222 having a helical cam groove of such pitch that the shaft may be rotated by a cam follower engaged in the groove and moved parallel to the axis of the shaft 221. Such a cam follower, illustrated as a roller 223, is mounted directly upon the slider 181 hereinabove described, which slider may be connected through the 20 transmission to the clutch operating lever 95.

The torch itself may be of any known form for the burning of a gaseous fuel in a jet of desired dimensions and producing a desired degree of heat. The nature of the gaseous fuel and whether it is burned in admixture with air or with a more strongly oxidizing gas, such as oxygen, do not constitute limitations on our invention. By way of example, we may use acetylene or natural gas as the fuel, with or without oxygen. The torch will have those features of adjustment conventional in known torches so that the size and shape of the jet and the amount of heat produced can be varied in accordance with specific requirements. It will be understood that the quantity of heat produced per unit of time by the flame will be proportioned to the degree of heat required for specific sealing operations and the speed of travel of the material being sealed through the machine.

We have, however, found it readily possible to effect seam formation positively, continuously and without skips by applying heat to the film materials through a metallic band from a torch or flame essentially confined, except for a narrow line of contact with the belt in a fluid cooled housing as described; and the flame, used as herein taught, serves to heat the belt or band uniformly so as to effect welding without skips in spite of sporadic displacements of the band, such as may be due to kinks or bends therein, providing the supporting means used opposite the band serves to keep the film materials in contact therewith.

Modifications may be made in our invention without departing from the spirit of it. Having thus described our invention in an exemplary embodiment, what we claim as new and desire to secure by Letters Patent is:

1. In seaming apparatus for seaming lapped film portions, an elongated forming plate about which film is drawn and tubed, said forming plate having a longitudinally extending opening therein, a series of transversely disposed rollers rotatively mounted in said opening, said rollers acting at the top surface of said forming plate to provide a moving support for the lapped film portions, a moving belt extending along said forming plate and overlying said rollers, and heating means located above said rollers,

and juxtaposed to said belt to apply heat to said belt.

2. In seaming apparatus for seaming lapped film portions, an elongated forming plate about which film is drawn and tubed, said forming plate having a longitudinally extending opening therein, a series of transversely disposed rollers rotatively mounted in said opening, said rollers acting at the top surface of said forming plate to provide a moving support for the lapped film portions, a moving belt extending along said forming plate and overlying said rollers, and heating means located above said rollers and juxtaposed to said belt to apply heat to said belt, said heating means being juxtaposed only to the central portion of said belt so as to establish a temperature gradient between the center and edge portions of said belt.

3. In seaming apparatus for seaming lapped film portions, an elongated forming plate about which film is drawn and tubed, said forming plate having a longitudinally extending opening therein, a series of transversely disposed rollers rotatively mounted in said opening, said rollers acting at the top surface of said forming plate to provide a moving support for the lapped film portions, a moving belt extending along said forming plate and overlying said rollers, and heating means located above said rollers and juxtaposed to said belt to apply heat to said belt, said heating means being juxtaposed only to the central portion of said belt so as to establish a temperature gradient between the center and edge portions of said belt, and a cooler located beyond said heating means in the direction of travel of said belt, said cooler being juxtaposed to said belt.

4. In seaming apparatus for seaming lapped film portions, an elongated forming plate about which film is drawn and tubed, said forming plate having a longitudinally extending opening therein, a series of transversely disposed rollers rotatively mounted in said opening, said rollers acting as the top surface of said forming plate to provide a moving support for the lapped film portions, a moving belt extending along said forming plate and overlying said rollers, heating means located above said rollers and juxtaposed to said belt to apply heat to said belt, said heating means comprising a torch and shield, said shield comprising a trough-shaped element adapted to be brought against said belt and presenting a slot thereagainst through which a flame can be directed against said belt, the walls of said trough-shaped element being hollow and fluid cooled.

5. In seaming apparatus for seaming lapped film portions, an elongated forming plate about which film is drawn and tubed, said forming plate having a longitudinally extending opening therein, a series of transversely disposed rollers rotatively mounted in said opening, said rollers acting as the top surface of said forming plate to provide a moving support for the lapped film portions, a moving belt extending along said forming plate and overlying said rollers, heating means located above said rollers and juxtaposed to said belt to apply heat to said belt, said heating means comprising a torch and a shield, said shield comprising a trough-shaped element adapted to be brought against said belt and presenting a slot thereagainst through which a flame can be directed against said belt, the walls of said trough-shaped element being hollow and fluid cooled and means for moving said torch

from a position in which said flame plays against said belt through said slot, to another position in which said flame is directed away from said slot.

6. In apparatus for the purposes described, a first seaming section comprising an elongated forming plate about which a film is drawn and tubed, said forming plate having a longitudinally extending opening therein, a series of transversely disposed rollers rotatively mounted in said opening, said rollers acting at the top surface of said forming plate to provide a moving support for the lapped film portions, a moving belt extending along said forming plate and overlying said rollers, heating means located above said rollers and juxtaposed to said belt to apply heat thereto, cooling means located beyond said heating means in the direction of travel of said belt, said cooling means being juxtaposed to said belt, pinch roll means for withdrawing the formed tube from said forming plate, cutting means for severing the formed tube into bag tube lengths, a first conveyor for moving the bag tube lengths longitudinally, a second conveyor at an angle to said first conveyor for moving the bag tube lengths transversely through a second seaming section, transfer means for transferring said bag tube lengths to said second conveyor, said transfer means comprising means for directing an air blast against the under sides of said bag lengths during said transfer, said last mentioned means including air tubes extending in the direction of said second conveyor and carrying adjustable vanes tiltable to a position in which the air blast is directed in the direction of motion of the bag tubes as they leave the said first conveyor, and seaming means in the second seaming section for seaming the ends of the bag tube lengths.

7. In combination for the purposes described, an elongated forming plate about which a web of material is drawn and tubed, said forming plate having a longitudinally extending opening therein, a series of transversely disposed rollers rotatively mounted in said opening, said rollers acting at the top surface of said forming plate to provide a moving support for the tubed web of material, and means for drawing the web material about said forming plate.

8. In combination for the purposes described, an elongated forming plate about which a web of material is drawn and tubed, said forming plate having a longitudinally extending opening therein, a series of transversely disposed rollers rotatively mounted in said opening, said rollers acting at the top surface of said forming plate to provide a moving support for the tubed web

of material, said rollers having a diameter substantially equal to the thickness of said forming plate, and means for drawing the web material about said forming plate.

- 5 9. A process of forming continuous seams by heat fusion in readily fusible films which comprises continuously moving the film in a path, juxtaposing film portions for seam formation by tubing the film, bringing the juxtaposed film portions against a band element traveling with the tubed film, applying heat to the juxtaposed film portions through said band under conditions of a temperature gradient such that the central portion of the band is at fusion temperature of the material of the film while laterally outlying portions of the band are below the fusion temperature, and movingly supporting the lapped seam portions internally of the tube during contact with the band.
- 10 10. A process of forming continuous seams by heat fusion in readily fusible films which comprises continuously moving the film in a path, juxtaposing film portions for seam formation by tubing the film, bringing the juxtaposed film portions against a band element traveling with the tubed film, applying heat to the juxtaposed film portions through said band under conditions of a temperature gradient such that the central portion of the band is at fusion temperature of the material of the film while laterally outlying portions of the band are below the fusion temperature, and movingly supporting the lapped seam portions internally of the tube during contact with the band, and thereafter cooling said band to bring the central portion thereof below the said fusion temperature during continued joint movement of tubed material and the belt.
